PRESSURE FLUID OPERATED TOOL

Ernest H. Shaff, Grand Haven, Mich., assignor
to William H. Keller, Inc., Grand Haven, Mich.,
a corporation of Michigan

Application October 26, 1931. Serial No. 571,009

6 Claims. (Cl. 121—19)

The invention relates to pressure fluid operated tools and more particularly to a new and improved portable tool of the hammer type.

The primary object of the present invention is to produce a tool of this character embodying novel valve structure of simple and economical form, constructed to produce a tool of minimum overall length capable of rapid and efficient operation.

10 Another object is to produce a new and improved valve structure for tools of this character arranged so that the parts thereof may be constructed and assembled by a relatively small number of simple manufacturing operations.

15 Other objects and advantages will become apparent from the following description taken in connection with the accompanying drawing which illustrates a preferred embodiment of the invention.

20 In the drawing:

Figure 1 is a central longitudinal sectional view of a pressure fluid operated hammer embodying the features of the invention.

Fig. 2 is an enlarged transverse sectional view 25 of the valve casing taken along the line 2—2 of Fig. 3.

Fig. 3 is an enlarged cross sectional view of the valve casing taken along the line 3—3 of Fig. 2.

Fig. 4 is an enlarged sectional view taken along 30 the line 4—4 of Fig. 1 to show the manner in which the valve members are held in place.

Fig. 5 is a side elevational view of one of the valve members.

In the embodiment illustrated in the drawing 35 the tool is of the type generally referred to as a chipping hammer, which comprises an elongated barrel 10 providing a cylinder or piston chamber 11 within which a piston 12 is reciprocable to impact a tool 13 mounted at the forward end of the barrel 10. Screw threaded on the other or rear end of the barrel 10 is a head 14 which constitutes the handle of the tool and has passages 15 and 16 therein through which pressure fluid is supplied under the control of a manually operated 40 valve 17. Pressure fluid, after passing the valve 17, is admitted alternately to opposite ends of the cylinder 11 by a suitable valve mechanism mounted at the rear end of the barrel 10 and held in place thereon by the head 14. This admission of pressure fluid serves to reciprocate 45 the piston, the exhaust of pressure fluid from the cylinder being controlled by the piston 12 in its reciprocatory movement.

The preferred form of valve mechanism comprises 50 an annular valve casing 18 positioned in

abutment with the rear end of the barrel 10 within in a sleeve 14^a formed as an integral part of the head 14 and which surrounds the rear end of the barrel 10 so as to provide the screw threaded connection between the barrel and the head. 60 Thus the valve casing 18 is held in place on the barrel by the head 14. Preferably the casing 18 is formed from a flat circular plate having a central bore 19 therein of such size as to form the rear end of the piston chamber. 65

The fact that the casing thus provided is relatively thin and serves as a portion of the piston chamber results in a marked reduction in the overall length of the tool.

In the present instance two thin flat valve 70 members 20 are provided, both mounted in the casing 18 and acting in unison to control the passage of pressure fluid to the opposite ends of the cylinder 11. The two valve members 20 are of similar rectangular shape, as shown in Figs. 1 and 5 of the drawing, and are preferably formed from a comparatively thin flat strip of spring steel. Said valve members 20 are mounted in chambers 21, formed by cutting relatively deep parallel grooves from the rear side of the casing on opposite sides of the piston chamber. These grooves are of a radial width slightly greater than the thickness of the valve members so as to permit shifting of the valve members alternately into contact with the opposite side surfaces of the 75 chambers. 80

In their shifting movement, the valve members alternately close opposed radial passages 22 and 23 opening into the valve chambers 21 at opposite sides thereof. The passages 22 and 23 are preferably formed by a plurality of parallel bores extending substantially radially through the valve casing 18 so as to intersect the chambers 21 at a plurality of points (Fig. 2) spaced longitudinally of the valve chambers. Thus the inner ends of the bores constitute the passages 23 which open 85 into the rear piston chamber. 90

To provide a connection with the front end of the cylinder 11, a passage 25 is formed for each of the valve chambers extending longitudinally of the valve casing 18 into communication with the central one of the passages 22. Each of these passages 25 communicates with a longitudinally extending passage 26 formed in the wall of the cylinder. The passages 26 are connected to the forward end of the cylinder 11 by means of transverse ports 27. Registry of the passages 25 and 26 is insured by dowels 28 fixed in the barrel 10 and extending into holes 29 (Fig. 2) formed in the valve casing 18. In order to connect all three of 100 105 110

the passages 22 with the passage 25, the head 14 within the sleeve 14^a is formed so as to provide an annular space 30 around the outer edge of the valve casing 18.

It will be noted that the valve chambers 21 open through the rear end surface of the valve casing 18 adjacent to the head 14 so that when the head is removed, the valve members 20 may be easily removed edgewise from the valve chambers. To provide for communication between the passage 16 and the valve chambers 21, an annular groove 31 is formed in the head 14 in the surface thereof which engages the rear end surface of the valve member 18 and communicates with the chambers 21 in any rotative position of the head. The groove 31 is so located and proportioned that its edges overlie the ends of the two valve chambers 21 as shown in Fig. 4 of the drawing, whereby to hold the valve members 20 in place in the valve chambers 21.

By this arrangement, the groove 31 is adapted to supply pressure fluid to the chambers 21 on either side of the valve members 20. Also, it will be seen that the head 14 holds the valve member 18 in place on the barrel 10, that it holds the valves 20 in position within the valve chambers 21, that it provides air supply passages to the valve chambers and between the various outlet passages of the two valve chambers, and that it serves as an end wall for the rear end of the cylinder 11.

The simplicity of the manufacturing operations involved in producing the present valve mechanism will be apparent from a consideration of Figs. 2 and 3 which show clearly the formation of each valve chamber 21 by cutting a straight slot across the rear face of the valve casing 18 substantially along a chord thereof. This slot in the present instance extends through the side edges of the valve casing and to define the ends of the chamber 21, the two ends of the slot are plugged as by forming bores 32 at spaced points along the slot and placing plugs 33 therein. This provides a valve chamber of rectangular form so that it is suited for the flat rectangular valve member shown in Fig. 5. It will be noted that in the preferred form, the slots which provide the two valve chambers 21 are parallel to each other so as to simplify the manufacturing operations involved. Also the bores forming the passages 22 and 23 are parallel to each other and the corresponding passages for the two chambers 21 are formed in alignment with each other.

To provide for exhausting the pressure fluid from the cylinder 11, a plurality of ports 34 are formed in the wall of the cylinder and are connected to longitudinally extending passages 35. The passages 35 communicate with atmosphere through ports 36 extending through the barrel 10 into a perforated guard 37 of conventional construction. The exhaust ports 34 are spaced from the ends of the cylinder 11 so that after the pressure has been exhausted from one end of the cylinder, the return movement of the piston 12 closes the exhaust ports 34 of that end of the cylinder during the terminal portion of the return stroke. This closing of the exhaust ports causes compression of air in the ends of the cylinders so as to cause shifting of the valve members 21 in a manner which will be more fully described in the following outline of the operation of the tool.

Assuming that the parts are in the position shown in Fig. 1, pressure fluid is being admitted from the annular passage 31 through the valve

chamber 21, and the passages 23 into the rear end of the cylinder 11 so as to cause forward movement of the piston 12. It will be noted that the piston 12 has covered the forward exhaust ports 34 so that the air trapped in the forward end of the cylinder 11 will be compressed as a forward movement of the piston 12 continues. The pressure thus built up acts through the passages 27, 26, 25 and 22 to exert a force upon the valve members 20 tending to shift these members to their inner positions. By reason of the passage 30 connecting all of the passages 22, it will be seen that this pressure will be exerted at points spaced longitudinally of the valve members 20. In the continued forward movement of the piston 12, the rear exhaust ports 34 are uncovered so that the pressure may be exhausted from the rear end of the cylinder. Since the valves 20 have been shifted as above described, rearward movement of the piston 12 is initiated and after the rear exhaust ports 34 have been covered, the valves are again shifted in the manner above outlined.

I claim as my invention:

1. In a pressure fluid operated hammer having an elongated barrel providing a piston chamber, a valve casing mounted at the rear end of the barrel and having a narrow valve chamber formed therein opening through an outer surface of the plate and positioned substantially perpendicularly with relation to the surface through which it opens, a relatively thin valve member adapted for edgewise insertion into said valve chamber, passages formed in said plate opening into said valve chamber on opposite sides of the valve member and communicating with opposite ends of the piston chamber, and a head secured on the barrel and abutting the valve member to hold the same in the chamber, said head having a passage therein arranged to supply pressure fluid to the chamber on either side of the valve member.

2. A pressure fluid operated hammer having a wall defining one end of a piston chamber, a head secured on the rear end of said wall, said wall having a narrow slot cut therein forming a valve chamber spaced from the inner and outer surfaces of the wall and opening edgewise through the rear end surface of the wall, a thin valve member in said valve chamber, passageways from opposite sides of said valve chamber to opposite ends of the piston chamber, and a passageway through said head for supplying pressure fluid to said valve chamber.

3. A valve casing for pressure fluid operated tools comprising a plate having a transverse slot formed therein extending partially through the plate from one side thereof, and plugs extending into said slot at points spaced longitudinally thereof to define the ends of a valve chamber, and passages formed in the plate opening into said chamber on opposite sides thereof.

4. A valve mechanism comprising an annular valve casing adapted to constitute a continuation of the cylinder of a pressure fluid operated hammer, said casing having a pair of parallel slots cut therein on opposite sides of its central opening, plugs positioned in said slots at spaced points to define a valve chamber in each of the slots, and said casing having a bore formed therein extending entirely from one side to the other and intersecting both of said slots intermediate said plugs.

5. A valve casing for pressure fluid operated hammers comprising a plate having a narrow slot formed therein extending partially through the

plate from one side thereof, plugs extending into said slot at points spaced longitudinally thereof to define the ends of a valve chamber, and a plurality of passages formed in the plate and intersecting said slot intermediate said plugs so as to provide openings into said chamber on opposite sides thereof at points spaced longitudinally of the chamber.

6. A valve mechanism for pressure fluid operated tools comprising an annular valve casing adapted to constitute a continuation of the cylinder of a pressure fluid operated hammer and

also having a pair of relatively small bores eccentrically positioned and parallel to each other, said plate having a slot cut therein centered on the plane defined by the axes of said small bores and of a width less than the diameter of said small bores, and plugs tightly fitted in said small bores to define a valve chamber in said slot, and said plate having passages formed therein extending into opposite sides of the slot between said plugs.
